UNITED STATES PATENT OFFICE.

ALBERT M. BULLARD, OF NEW YORK, N. Y., ASSIGNOR, BY MESNE ASSIGNMENTS, TO
WESTERN ELECTRIC COMPANY, INCORPORATED, A CORPORATION OF NEW YORK.

AUTOMATIC TELEPHONE-EXCHANGE.

1,327,805.

Specification of Letters Patent.

Patented Jan. 13, 1920.

Application filed March 12, 1906. Serial No. 305,548.

To all whom it may concern:

Be it known that I, ALBERT M. BULLARD, citizen of the United States, residing at New York, in the county of New York and State of New York, have invented a certain new and useful Improvement in Automatic Telephone-Exchanges, of which the following is a full, clear, concise, and exact description.

10 My invention relates to an automatic telephone exchange system arranged to accommodate a large number of lines, for example, ten thousand, and its object is to provide an improved organization of circuits and 15 apparatus by which the selective switching of any two subscribers' instruments into connection with each other may be accomplished rapidly and with certainty, while meeting the various requirements of signaling, prevention of interference with busy 20 lines, good telephone transmission and economy of current consumption.

My invention contemplates an exchange provided with "hundreds selectors," and 25 "tens-and-units" selectors for making connection between a calling and called line under the control of the calling station. Each line in the exchange terminates upon a number of groups of contacts, each group 30 with its contact arm and the mechanism therefor being designated as a "tens and units" selector. Each line also has at the central office a distributor individual thereto, which is adapted upon the closure of the 35 substation switch of such line to automatically connect the line with an idle "hundreds" selector. Each hundreds selector is provided with contacts representing the hundreds digits of the lines in the exchange, 40 and the subscriber at a calling station is provided with means for operating the selector connected therewith by the distributor, to bring the selector into connection with any hundreds contact, to connect the calling 45 line with the contact representing the hundreds digit of the line with which connection is desired. The distributor when operated disconnects from the calling line the terminals representing such line upon 50 the tens and units selectors, and applies thereto a source of test current, said terminals remaining disconnected until the distributor is returned to its normal position.

The contact representing the hundreds

digit of the called line is connected with a 55 finder which is operated when a calling line is connected to such hundreds digit contact to connect said contact with an idle tens and units selector, such tens and units selector being adapted to be operated from the 60 calling station to connect the calling line with the terminals of the called line. The calling station is equipped with a ringing key adapted to apply ringing current to the called line. When the tens and units selector 65 makes connection with the terminal of the called subscriber, a test potential is applied to the remaining terminals of such line. After conversation is terminated, and the subscribers hang up their telephones, the apparatus is automatically returned to its normal 70 position.

In case the called line were busy, the two 75 selectors and the finder for selecting an idle tens and units selector would be immediately returned to their normal positions and a 80 source of busy tone current applied to the calling line, the mechanism associated with its distributor remaining operated, since it is under the control of the calling station. Thus, if the calling subscriber is slow in comprehending the busy signal, and is slow 85 in hanging up, his individual distributor is tied up, but no common selectors. Each hundreds selector is adapted to make connections for a given number of subscribers, for example, ten, and each distributor may have, say, five trunk lines, one leading to the hundreds selector apportioned to it, and the other four running to other trunk 90 selectors, so that in case of two or more simultaneous outgoing calls from a group of subscribers associated with one hundreds selector, other hundreds selectors are available.

A feature of the invention lies in the improved organization of circuits and apparatus whereby a central source of current-supply may furnish energy to all the lines, and whereby the required switching, testing and other operations are performed without 100 requiring more than two main conductors for any line or trunk, or more than two sets of multiple terminals for any circuit. That is to say, there is not required a special set of test-terminals and "private normal" for each 105 line or trunk, as the two main line-terminals (multiplied where necessary) are sufficient. It has been usual heretofore in automatic

exchanges to provide a selector individual to each line, to be controlled through the agency of the transmitter mechanism at the substation. Such selectors are complicated 5 and expensive pieces of apparatus; and it is an advantageous feature of this invention that instead of requiring such a selector for each line, a comparatively cheap and simple automatic distributor may be employed as 10 the individual terminus of each line, only a few of the more expensive selectors being required to handle the calls for a large group of lines, an idle selector being automatically secured by the distributor of any line when 15 the line is taken for use.

I will describe my invention more particularly by reference to the accompanying drawings, which illustrate the preferred embodiment thereof, the particular features which 20 I deem novel with me being set forth in the appended claims.

Figures 1, 1^a, 1^b, 1^c, considered together represent diagrammatically the complete circuits of two connected subscribers. In 25 association with each of these figures is a supplemental diagram indicating means for operating certain contacts which upon the supplemental diagrams are indicated by the same reference letters that appear upon the 30 corresponding contacts shown in the circuits.

Fig. 2 is a simplified diagrammatic representation of the talking circuit of a completed connection; and

Fig. 3 represents in outline the trunking 35 system employed in my invention.

Referring first to Fig. 3. I have shown three groups of subscribers, each associated with a hundreds selector. In the present case I have shown ten subscribers to a group, 40 but it will be understood that any number desired may be included. Each subscriber is provided with a distributor *a* having trunk lines *a'* extending to the hundreds selectors, three of which are shown. Each group of 45 subscribers is provided with a hundreds selector for its own especial use, one trunk line leading from each distributor of the group to the hundreds selector *H*. The hundreds selector is provided with contacts 50 representing the hundreds digits of the lines in the exchange, and each hundreds contact is connected with a finder *E* provided with trunk lines running to the tens and units selectors *B*, each such selector having associated therewith terminals representing the 55 tens and units associated with the particular hundreds digit terminal with which its finders are associated,—that is, the hundreds contact 49 would be connected with a 60 finder provided with trunk lines leading to tens and units selectors having terminals 4900 to 4999.

With this brief outline of the trunking system, I will now proceed to describe the apparatus and circuit connections at the 65

substation and central office in detail. In the drawings Figs. 1, 1^c, I have shown two subscribers' lines, *A*, for example, No. 400, which we will designate the calling line, and *B*, No. 4899, for example, which we will designate the called line, both extending to their multiple line terminals at the central office. Since the substation apparatus of both lines would be the same, and their central office connections the same, I have simply shown the connections at substation A. 70

The operating mechanism of the hundreds selectors and tens-and-units selectors may be similar to that of the selectors shown in the prior patent to myself and M. C. Rorty, No. 75 709,740, dated September 23, 1902.

Substation equipment.

The subscriber's station equipment includes, in addition to the usual telephone apparatus, an interrupter *C*, which by two successive manipulations controls the operation of the hundreds and of the tens and units selectors as will be hereinafter explained. The interrupter forms no part of the present 90 invention, being a well known type. The apparatus and circuits of the interrupter will be described in detail hereinafter in connection with the hundreds selector. 95

Individual distributor.

As before stated, each line is provided at the central office with a distributor *a* individual thereto, adapted to automatically connect the same with an idle hundreds selector in response to a call. Each distributor comprises a set of contacts *a'* connected by trunk lines *a'* with a number of hundreds selectors, the first contact being preferably connected with the hundreds selector apportioned to the group of lines containing the line to which the distributor is individual. An arm *a*³ is arranged to trail over the contacts of the selector. As shown in the diagram, there are two distributors, one for 100 each limb of the line, but it will be understood that in practice these distributors would be one structure, with a single contact arm carrying a pair of wiping contacts. As shown, however, the limb 1 terminates 105 upon the contact arm *a*³, while the limb 2 terminates upon a similar contact arm *a*⁴ arranged to sweep over terminals *a*⁵, each contact *a*⁵ being connected with a trunk line *a*¹¹ leading to a hundreds selector. The continuity of the conductors 1, 2, is normally broken at the central office, but is adapted to be closed to connect the line with the distributor by a relay *b*. At the central office 110 the battery *D* is in a bridge 3 of the line, being grounded at its middle point by a conductor 4, a relay *c* being included in said bridge between the positive pole of the battery and the limb 1 of the line, while a relay *c'* is included in said bridge between the 115 120 125 130

negative pole of the battery and the limb 2 of the line. The armature c^2 of relay c is connected by conductor 5 with the bridge 3 between the battery D and relay c , and the 5 front contact c^3 of the armature is connected with conductor 6, which extends through the stepping magnet d to the front contact e' of a test relay e , a branch 7 extending from said conductor through a retaining 10 magnet f to the negative pole of battery D, said conductor also including the armature and back contact of a relay g , which, however, is not concerned in the operation of calling. The stepping magnet d is adapted 15 to operate an armature d' which carries a pawl adapted to engage the teeth of a wheel d^2 carried by the shaft to which the contact arms a^3 a^4 are connected, and the retaining magnet f is provided with an armature f' 20 carrying a detent adapted to engage the wheel and maintain it in an operated position. The armature f' is connected by a conductor 8 with the back contact b^2 of armature b' of magnet b , said armature being included in the portion of line conductor 1 connected with the arm a^3 . The armature f' of the retaining magnet is provided with a front contact f^2 connected with a conductor 9 leading to earth through the test relay 25 30 e . The armature of the testing relay is connected by a conductor 10 with the negative pole of battery D by means of conductor 7. When the subscriber removes his telephone from its hook to initiate a call, a 35 metallic circuit 1, 3, 2, is completed, including battery D and relays c c' . Relay c , in drawing up its armature completes a circuit 3, 5, 6, 7, 3, including battery D and retaining magnet f , which connects the test relay 40 e with the distributor arm a^3 by means of conductors 1, 8, 9. Now if the hundreds selector connected with the first trunk line of the distributor a is engaged, there will be a potential at the first contact a^2 furnished 45 by a battery associated with the other calling line, and referred to later, and the relay e will be energized, drawing up its armature and completing a circuit 3, 5, 6, 10, 7, 3, including the stepping magnet d . The 50 magnet d thereupon attracts its armature d' , and by means of a ratchet and ratchet wheel operated thereby, advances the distributor springs a^3 a^4 one step to the next pair of terminals connected with the second trunk line. The spring a^3 , in passing between the 55 terminals, momentarily opens the test circuit through relay e , which thereupon releases its armature. If the second pair of terminals leads to a hundreds selector that is already 60 engaged, current again energizes the test relay, and the operation of the stepping magnet is repeated, and continues to be repeated until an idle selector trunk is reached, when the test relay e remains deenergized and the 65 stepping magnet d settles back into resting

position, the retaining magnet, however, remaining energized in its circuit 3, 5, 6, 7, 3, to hold the contact arms a^3 a^4 in their advanced position.

The armature d' of relay d is connected 70 by a conductor 11 with conductor 6, and is adapted when retracted to close contacts d^3 connected by a conductor 12 with conductor 7, said conductor 12 including the relay b . Thus when the relay c is energized, and 75 magnet d deenergized, a circuit 3, 5, 6, 11, 12, 7, 3, would be completed for the magnet b , which, when energized, completes the continuity of conductors 1 and 2, connecting the same directly with the springs a^3 a^4 of 80 the distributor. However, during the rapid vibrations of the armature of the stepping magnet d , the contacts d^3 are agitated to such an extent that insufficient current passes through them to operate the cut-off 85 relay b ; but when the armature of relay d comes to rest in its backward position, an increased amount of current passes through and operates the relay b , which thereupon opens the test circuit of relay e at contacts 90 b' b^2 , completing the circuit 1, 2, for voice transmission at contacts b' b^3 and b^4 b^5 respectively. To increase the working margin between non-operating and operating currents, the relay b may be rendered sluggish in any of the well known ways, as by a heavy closed secondary winding, or the contacts d^3 may be weighted and spring-supported, or both plans may be adopted.

The cut-off relay b , by opening the circuits of the test relay and stepping magnet, prevents further progression of the distributor arms a^3 a^4 , the retaining magnet f by means of its detent, maintaining the distributor arms in their advanced position as long 105 as relay e remains energized.

The rotary movement of the shaft of the distributor opens contacts a^6 a^7 to separate the line of subscriber A from the multiple terminals A' of limb 2 of the line. The 110 distributor shaft also separates spring a^8 from its contact anvil a^9 , which is connected with line conductor 1, and moves said spring a^8 into connection with contact a^{10} , which is connected with a grounded source of busy 115 test current D', said spring a^8 being connected with the test terminals A' of the line to station A, said test terminals constituting the multiple terminals of limb 1 of the line.

Let us assume that the sixth pair of terminals a^2 a^5 has been secured, and that from them runs a trunk a' a^{11} to the hundreds selector H shown in Fig. 1^a.

Hundreds selector.

As before stated, a number of hundreds selectors are provided, each capable under average conditions of transmitting the calls originating from a group of the subscribers, 130

each selector having a trunk line running from its contact arm in multiple to a number of subscriber's distributor. Each hundreds selector is provided with contacts h representing the hundreds digits of the lines of the exchange, and with a contact arm h' adapted to be moved over the contacts h by a stepping magnet i , and be drawn down into connection with the desired contacts by a connecting magnet k . It will be understood that the contact arm h' is provided with two contact terminals adapted to be brought into engagement with a pair of contacts connected with the limbs of a trunk line leading to a finder E, but for convenience of illustration I have shown two selectors, one in each limb of the extended line. The contact arm is adapted to be stepped forward above its terminals, and when the desired one is reached to be drawn into connection with such terminals by a suitable magnet. The limbs a' a^{11} of the trunk line or extension of line conductors 1, 2, lead through normally open contacts of a cut-off relay l to the arms h' of the hundreds selector.

The hundreds selector is equipped with relays m m' in the bridge 12' of trunk conductors a' a^{11} , said bridge including a battery D^2 grounded at its middle point by a conductor 12^a. The relay m' is operated the moment the cut-off relay l associated with the distributor closes contacts b^4 b^5 , for current thereupon flows from the negative pole of battery D^2 through relay m' , trunk conductor a^{11} , contact a^5 , arm a^4 of the distributor, contacts b^4 , b^5 , of the connecting magnet, line conductor 2, through the substation apparatus, and back over conductor 1 through relay c to the positive pole of battery D . The relay m' is provided with an armature m^2 adapted when attracted to close a pair of contacts m^4 insulated from said armature and controlling a short circuit 15 about the normally open springs h^2 h^3 included in trunk conductor a' , thus completing a metallic circuit by way of conductors 12', a' , 1, 2, a^{11} , for the relays m m' . The contacts h^2 h^3 are adapted to be closed together when the hundreds selector arm is away from its normal position, but are normally open, so that the contacts connected with the hundreds selector at the several subscribers' distributor will not have a potential thereat when the hundreds selector is idle. It will be noticed that immediately upon the energization of relay m' associated with a selector with which a distributor makes connection, potential is applied to the multiple contacts a^2 connected with the trunk conductor a' at the several subscribers' distributor with which this particular hundreds selector is associated, so that as explained in connection with the distributor of line A, its arm upon reaching such con-

tact will complete a circuit from battery D^2 for its test relay e and be moved to the next terminal of the distributor.

The relays m m' control the operation of the stepping and connecting magnets i k of the hundreds selector. The front contact m^5 of relay m' is connected by conductor 16 with the bridge 12' of the trunk conductors a' a^{11} between the positive pole of battery D^2 and the relay m , and the armature m^6 of said magnet, which when attracted engages contact m^5 , is connected with a conductor 17, which leads through the stepping magnet i and a retaining magnet n in series, through the normally closed contacts k' of the connecting magnet k , armature o^2 and its back contact of a relay o to the bridge 12 between relay m' and the negative pole of the battery. The connecting magnet k is in a branch 18 leading from conductor 17 to normally open contacts i' of the stepping magnet i connected with conductor 17. The stepping magnet i is provided with an armature controlling said contacts and carrying a pawl adapted to engage a ratchet wheel on the shaft carrying the contact arms h' of the selector in the well-known manner, to step said wheel around and advance the contact arms h' , while the magnet n is provided with an armature carrying a detent adapted to engage the ratchet wheel to maintain the same in its advanced position.

Thus when contacts m^5 m^6 of relay m' are closed, a circuit 12', 16, 17, 12' is completed for magnets i n , whereupon the arms h' of the hundreds selector are advanced one step. The circuit of connecting magnet k , as before stated, is controlled by the contacts i' , which are closed by stepping magnet i when energized. These contacts when rapidly agitated are of high resistance. Agitation is effected by the quick reciprocating movement of the armature, and said contacts, therefore, do not permit the energization of the connecting magnet k until the arm reaches the desired terminal, when the contacts touch together firmly and complete a circuit 12', 16, 17, 18, k , 17, 12', whereupon connecting magnet k is energized to draw the arms h' down upon the desired hundreds digit terminals. The magnet k when energized attracts its armature k^2 , which separates contacts k' , engaging the member of said contacts connected with the negative pole of battery D^2 and so completing a circuit for itself independent of the contact i' .

In order to thus step the hundreds selector arm to the desired hundreds digit terminal, it is necessary to alternately open and close the circuit of magnet m' , and this is effected by means of the interrupter C at the substation. Let us assume that the number of subscriber B with whom subscriber A desires connection is 4899, as shown in the drawings. 130

The subscriber A would then be obliged to secure connection with the contact terminals 48 upon a hundreds selector.

The interrupter comprises a toothed wheel d^5 arranged to successively close a pair of contacts d^6 as the teeth of the wheel pass in succession over the end of one member of said contacts. A controller arm d^7 is arranged to be moved forward loosely upon the axis of the wheel against the tension of a coiled spring, and carries a pawl, which, as the controller arm is returned by the spring after its advance, engages the ratchet wheel d^5 to carry the same around with it, whereby the contacts d^6 are made and broken a certain number of times, dependent upon the distance to which the controller arm has been advanced. In practice I provide upon the face plate of the interrupter over which the controller arm travels, a series of holes, each representing a tooth upon the ratchet wheel, the holes being numbered from 0 to 99. I provide a peg which may be inserted in any numbered hole, so that by moving the arm until it reaches the peg and releasing it, the ratchet wheel d^5 will be operated to make and break the contacts d^6 the number of times indicated by the number of the hole into which the peg is inserted. The calling subscriber's first act after lifting his telephone from its switch hook is to peg into hole No. 48 of the interrupter, and move the controller arm until it strikes the peg, and release it, whereupon it returns rapidly to zero. When the controller arm is moved away from its normal position, it first causes the closure of contacts n^1 n^2 . Contact n^1 is connected by a conductor 19 with the telephone hook, and so with limb 1 of the line, while contact n^2 is grounded by conductor 20. The closure of these contacts thus grounds limb 1 of the line through the telephone set. This causes relays c and m to remain energized, since they receive current from the upper halves of batteries D and D^2 respectively. Contacts n^3 n^4 are next connected, contact n^3 leading to the normally-open pair of contacts d^6 by way of conductor 21, and contact n^4 , which is included in limb 2, being at the same time separated from the contact n^5 also included in the line circuit. The metallic line circuit is now interrupted, relays c m remaining energized, however, since they are in a grounded circuit. The opening of the line circuit causes relays c m to release their armatures. The deenergization of relay c does not effect the distributor arms, because relay c is maintaining the excitation of the retaining magnet f by means of contacts c^2 c^3 . Relay m in releasing its armature m^6 allows the hundreds selector to become quiescent ready for the selective operation, it being understood that when relay m was first energized, it causes the

stepping magnet i to advance the hundreds selector contact arm one step,—an incidental movement devoid of significance. When the controlling arm of the interrupter is released, it returns by means of the spring to zero, and in returning alternately closes and opens the contacts d^6 , which alternately close and open a grounded circuit 21, 2, a^1 , 12', 12^a, including the relay m' . The armature m^6 of relay m' thereupon alternately closes and opens a local battery circuit through the stepping and retaining magnets, as previously traced. The contact arms h' of the selector are thus advanced and brought opposite the 48th pair of terminals h in the circle of one hundred terminals. The contacts i' remaining closed for an instant, the circuit 12, 16, 17, 18, 17, 12', is completed for the connecting magnet k , which draws down the arms h' upon the 48th pair of terminals, and also disconnects the magnets i and n from the selector.

Each pair of terminals on the hundreds selector is connected by trunk lines with a finder adapted to connect the same with an idle tens and units selector carrying line terminals representing the tens and units digits associated with the hundreds digit which said pair of terminals on the hundreds selector represents,—that is, the tens and units digits of the 48th hundred group of subscriber's lines.

When the controller arm of the subscriber's interrupter arrives at zero, it closes contacts n^4 n^5 and opens contacts n^3 n^4 , as well as contacts n' n^2 , so restoring the normal metallic circuit of the line, and disconnecting it from springs d^6 .

A branch conductor 17^a extends from conductor 17 through two pairs of normally open contacts h^4 h^5 , through the winding of the relay l controlling the continuity of conductors a' a^{11} leading to the contact arms of the hundreds selector, and passing thence through the normally open contacts of a relay p to the positive pole of a battery D^3 included in a bridge 17^b of the trunk conductors a' a^{11} , said battery being grounded at its middle point. The contacts h^4 are arranged to be closed by the selector contact arm h' when away from its normal position, and the contacts h^5 are arranged to be closed by the connecting magnet k when energized to complete a connection of contact arms h' with the hundreds terminals of a desired line, and when such connection has been completed a circuit from the negative pole of battery D^2 is completed by way of conductors 12^a, 12', 17, 17^a, 17^b, to the positive pole of battery D^3 and to ground, said circuit including relay l . This circuit also includes a pair of high resistance contacts d^7 controlled by the stepping magnet q of the tens and units finder, which immediately upon the ener-

gization of the connecting magnet would be operated to step the contact arm of the finder to an idle trunk, so making and breaking said contacts d^7 and preventing the 5 operation of relay l until such trunk has been selected.

Tens-and-units finder.

As shown in the present case, the 48th 10 pair of terminals is connected by a pair of trunk conductors 22, 22^a, with the finder E, adapted to automatically select an idle tens-and-units selector. The finder E is of the same construction as the distributor a individual to each line, and before described, 15 but for convenience of illustration it is provided with a pair of arms e^2 e^2 connected with trunk conductors 22, 22^a, and adapted to sweep over two sets of trunk terminals e^3 . The finder E is provided with a stepping 20 magnet q and retaining magnet q' and a test relay q^2 controlled by relays p p' in the bridge 17^b of the trunk conductors a' a^{11} . These relays p p' are operated at the same 25 time with relays m m' , but since the local circuits of their controlled apparatus are open at the contacts h^4 h^5 until the contact arms of the selector are brought down upon the desired terminals, these relays perform 30 no function until that moment arrives. A branch conductor 23 extends from the front contact of the armature of magnet p' through the test relay q^2 , back contact l' and armature l^2 of magnet l to the trunk conductor a' , which is connected by arm h' of the 35 hundreds selector with the trunk 22 leading to the arm e^2 of the tens and units finder.

The operation of the finder E is the same as the individual distributor a . If the tens-and-units selector to which the first trunk 40 line terminating on the first contact e^8 leads is busy, a test potential will be present at the first contact and a current will be passed by way of conductors 22, a' , 23, through 45 test relay q^2 to the front contact of relay p' , and thence through its armature, which is attracted, to earth. The test relay controls at its armature and front contact the continuity of a conductor 24 leading from the conductor 17^a through the stepping magnet q and front contact of relay p back to the conductors 17^a near its junction with the bridge 17^b, a branch 25 leading from conductor 24 through the retaining magnet 50 back to the conductor 17^a. Thus when the test relay is excited, it completes a circuit from conductor 17^a (which is connected with the negative pole of battery D^2) by way of conductors 24, 17^a and 17^b, to the 55 positive pole of battery D^3 , said circuit including the stepping magnet q . The retaining magnet is in a circuit independent of the selecting magnet, said circuit leading from the negative pole of grounded battery 60 D^2 by way of conductors 12^a, 17, 17^a, 25, 17^a,

17^b to the positive pole of grounded battery D^3 . The contact arms e^2 of the finder are thus automatically brought into connection with a trunk line leading to an idle tens and units selector. When this has been 70 done the armature of magnet q comes to rest and closes the heretofore high resistance contacts d^7 , whereupon current is permitted to flow in the circuit 12^a, 12^b, 17, 17^a, 17^b, to operate the cut-off relay l , thereby 75 completing the continuity of the trunk conductors a' a^{11} from their contacts on the distributor to the contact arms of the hundreds selector, cutting off the selecting and test relays of the tens and units finder, the 80 retaining magnet, however, remaining energized to hold the finder arms e^2 in their advanced position. From each pair of contacts on the tens and units finder E a pair of trunks lead to a selector representing the 85 tens and units associated with the hundreds digit selected, that is, since the 48th pair of terminals has been selected on the hundreds selector, trunk lines lead from such terminals to a finder having contacts, each 90 pair connected with trunks leading to a selector having terminals representing the lines numbered from 4800 to 4899.

Tens-and-units selector.

95

Let us assume that the first idle trunk line leading to an idle tens-and-units selector is the 6th. The apparatus associated with the tens-and-units selector is substantially the same as that associated with the hundreds 100 selector. From the sixth pair of terminals e^8 of finder E a pair of trunk conductors 26, 26^a lead to the contact arms r of the tens and units selector B', said arms r being adapted to sweep over contacts r' representing the lines 4800 to 4899, a condenser X' being included in conductor 26^a between the bridge 27 and the selector. The bridge 27 unites trunk conductors 26, 26^a, said bridge including relays s s' and a battery D^4 110 grounded at its middle point by a conductor 27^a, said battery being located between the two relays. As soon as the contact arms of the finder E make contact with the terminals of trunk conductors 26, 26^a, a circuit for the 115 relay s' is completed by way of conductors 27^a, 27, 26^a, 22^a, a^{11} , line conductor 2, through the substation apparatus and back over limb 1 of the line, conductor 3, to the positive pole of battery D and to ground 120 by way of conductor 4. The armature s^2 of relay s' is adapted when attracted to close a short circuit 26^b about a pair of normally open contacts r^2 included in trunk conductor 26, so completing a metallic circuit through 125 to the substation A, and operating the relay s . The closure of this short circuit applies test current from battery D^4 to the contacts of the tens and units selector B' upon its several finders E in the manner described in 130

connection with the hundreds selector and the individual distributor. The contacts r^2 in conductor 26 are arranged to be closed by the contact arm r of the tens-and-units selector when away from its normal position. The armature s^4 of relay s' when attracted completes the continuity of conductor 26^a leading to the finder.

The tens-and-units selector is provided 10 with a stepping magnet t and retaining magnet u , and a connecting magnet v controlled by the relays s s' . The conductor 28 extends from bridge 27 between the negative pole of battery D^4 and relay s' , through the 15 armature s^2 and its front contact, stepping magnet t and retaining magnet u in series, normally closed contacts v' v^2 controlled by connecting magnet v , armature I^5 and its back contact of relay I to the positive pole 20 of battery D^4 , a branch 29 extending from said conductor through the connecting magnet v and a pair of normally open high resistance contacts v^3 , back to conductor 28. During the vibration of the armature t' , the 25 contacts v^3 do not remain closed for a sufficient length of time to permit the relay v to be excited, but when the stepping magnet remains steadily excited upon the completion of a connection between contact arms r 30 of the tens-and-units selector and the called line, the connecting magnet v is energized and draws the arms r down upon the contacts of the called line and disconnects the stepping and retaining magnets from the 35 circuit as described in connection with the hundreds selector.

The calling subscriber at station A, in manipulating the interrupter arm with the peg now in hole 99, advances the arms r of 40 the tens-and-units selector in precisely the same manner as in the operation of the hundreds selector already described, that is, he operates the interrupter to make and break contacts d^6 one hundred times, thereby making and breaking the circuit of relay s' one hundred times, and stepping the contact arms r around to the pair of terminals representing line 4899. Each time the relay s' is energized, a circuit 27, 28, 27, is completed 45 for the stepping and retaining magnets t u , and when the arms are opposite the desired terminals and the contacts v^3 remain closed, a circuit 27, 28, 27, is completed for the connecting magnet v , which magnet draws the 50 arms r upon the contacts of the desired line, and opens at contacts v' v^2 the circuit of the stepping and retaining magnets, closing in addition a shunt around said high resistance contacts v^3 . Conductors 30, 30^a, lead from 55 the pair of terminals r' of the tens-and-units selector to the substation of line B.

In the drawing I have shown the distributor associated with the called line 4899. It is essential that this distributor should not 60 be operated when a call is received, and for

that purpose means are provided adapted to be operated when the arms r of the tens-and-units selector reach the terminals of a called line to render the distributor of such called line temporarily inoperative. To this 70 end I provide a relay F in a bridge 31 of conductors 30, 30^a, a condenser X being interposed in conductor 30 between bridge 31 and the individual apparatus of subscriber B at the central office, so that the 75 relay will only be operated when subscriber B is called, but will be unaffected when subscriber B is calling. The apparatus at the central office individual to line B is precisely the same as that described in connection with 80 line A, a bridge 3^a of the conductors 30, 30^a containing magnets w w' similar to the magnets c c' of line A, a battery D^5 being included in said bridge between the two relays, with its middle point grounded by a 85 conductor 3^b. These relays control the apparatus of the distributor. Thus when the contact arms r descend upon the terminals leading to station B a circuit for relay F is completed from the positive pole of battery D^4 by way of conductors 27^a, 27, 26, 30, 31, 30^a, 3^a and 3^b to the negative pole of grounded battery D^5 . The armature of relay F in drawing up its armature F', opens conductor 7^a and cuts off the supply of current to the distributor magnets. The relay F is of high resistance and impedance, and is very sensitive and efficient. Placed in series with relay w' it will operate upon a current strength that will fail to operate the 90 latter relay.

The relay F when energized, attracts its armature F', and close a shunt 32 about the magnet w' , said shunt containing an impedance coil x . Its armature F² when 105 attracted, closes a shunt 33 containing the impedance coil x' about the magnet w , said impedance coil being shunted out, however, by a conductor 34' whose continuity is completed by the armature w^2 of magnet w' when said magnet is deenergized. These 110 impedance coils are introduced into the circuits to provide current of adequate volume for voice transmission from the substation apparatus. To show the need of these impedance coils it is necessary to explain the relation of the various current supply relays to each other and to the whole circuit.

In the drawing, Fig 2, a completed connection is illustrated in so far as its talking 120 circuits are concerned, a single battery being shown for supplying the current for transmission. It will of course be understood that this single battery may be employed in the place of the several batteries 125 illustrated in the drawings, Figs. 1, 1^a, 1^b, 1^c. On the calling line are bridged two groups of relays inclusive of the battery, each group consisting respectively of the relays c m p s connected in multiple, and the relays c' m' 130

$p' s'$, also connected in multiple by the selective operations. On the called line there is but one relay on each side of the battery, that is, w and w' , belonging to the distributor of the called line. These groups are separated by the condensers $X X'$, so that each line receives its independent supply of current. Now it is evident that distributor relays $w w'$ are of the same resistance as distributor relays $c c'$, but relays $w w'$ are of too great resistance to permit a flow of current requisite for transmission when used independently. For example, assume each of the relays to have a resistance of 1000 ohms, which would make the combined resistance of relays $c m p s$ connected in multiple, 250 ohms, as against 1000 ohms of relay w . Now, by adding a $333\frac{1}{3}$ ohm impedance coil in multiple with each of the relays $w w'$, the combined resistance of relay w and impedance x , as well as relay w' and impedance x' , is 250 ohms. The position of the high resistance bridge relay F is shown in this figure in dotted lines.

25

Signaling.

The next step in the connection is the application of ringing current to the line of the called subscriber. This is done through the agency of a ringing key y at the calling station. The ringing key comprises a pair of normally connected contact springs $y' y^2$ serially included in the line circuit, and a spring y^3 connected with grounded conductor 20, said spring being adapted to be forced into engagement with contact y' and separate the same from its anvil y^2 . The relay s associated with the tens and units selector is provided with an armature s^3 connected by conductor 34 with the back contact of armature s^4 of relay s' , said armature s^4 being included with its normally open front contact in the trunk conductor 26^a, the front contact of armature s^3 of relay s being connected by conductor 35 with a grounded ringing generator G.

When the calling subscriber operates the ringing key, he first grounds the limb 1 of his line through contacts $y' y^3$, and conductor 20, and next separates contacts $y' y^2$, thereby opening the metallic circuit of the line and removing battery from limb 2 and trunk conductors $a^{11}, 22^a$ and 26^a . This latter action deenergizes the relays $c' m' p' s'$. The deenergization of these relays does not restore the selector arms to zero, because the work of holding them in place has been thrown upon relays $c m p s$, and the latter are still energized over a path from batteries D D^2 $D^3 D^4$ over the limb 1 of the calling subscriber's line to ground through the depressed ringing key y .

Before continuing the description of the ringing operation, I will explain how each

of the relays $c m p s$ holds the selector arms 65 in place. Relay c of the calling subscriber's individual distributor holds the contact arm a^3 in its advanced position by contacts c^2 c^3 and retaining magnet f in the circuit 3, 5, 6, 7, 3. 70

From the front contact m^7 of armature m^8 of relay m , the conductor 36 extends through two sets $h^6 h^7$ of normally open contacts to the conductor 17. Contacts h^6 are closed when the arm h' of the hundreds selector is away 75 from its normal position, and the contacts h^7 are closed by the connecting magnet when energized to complete a connection of the arms h' with a desired pair of terminals, so that when said contacts are closed a circuit 80 for the connecting magnet is maintained by way of conductors 12', 16, 36, 17, 18, 17, 12', independent of relay m' . The hundreds selector arm is thus held in its advanced position by relay m independent of relay m' . 85

The relay p associated with the tens-and-units finder holds the contact arm e^2 of the finder in its advanced position by means of a circuit 17^b, 17^a, 25, 17^a, 17, 12, 12^a, through the retaining magnet q' closed by its armature. 90

The relay s of the tens-and-units selector holds up the connecting magnet v of the tens-and-units selector in the same manner as the connecting magnet of the hundreds selector is held up. The armature s^5 of relay s is connected by a conductor 37 to the negative pole of battery D^4 and the front contact of said armature is connected by a conductor 38 with a conductor 28 which supplies current to the connecting magnet, said conductor 38 including two sets of normally open contact springs $r^3 r^4$. The contacts r^3 are adapted to be connected by the contact arm r of the selector while away from its normal position, and the contacts r^4 are arranged to be closed by the connecting magnet v when energized to draw the arm r down upon the contacts of a desired line, so that a circuit is thereby completed for magnet v independent of relay s' by way of conductors 27, 37, 38, 28, 29, 28, 27, including battery D^4 . 110

When the subscriber A presses his ringing key to ground the limb 1 of the line, the armatures of relay s' are retracted, and since relay s is energized and its armature is attracted, a circuit for ringing current will be completed from the ringing generator G by way of conductors 35, 34, trunk conductor 26^a, through contact arm r of the tens and units selector to the limb 30^a of the called line, thence through the substation apparatus and back over limb 30 of the line, through conductors 3^a, 33, 34', to front contact of armature F^2 of relay F, which armature is connected with the positive pole of battery D^5 , and thence to ground. To avoid 120

a disturbance of relay w' by ringing current traversing its winding in a shunt path from conductor 26^a to battery D⁵ and ground, said relay is polarized and biased, and the 5 ringing current made pulsating in character. As shown in the circuit, negative pulsating current is employed, and relay w' is so related to the battery and ringing current that it is operated by the former current but not 10 by the latter. Therefore the relay w' is not operated during the ringing. The contacts controlling the short circuit about relay w and the impedance coil x' remain closed until the called subscriber answers, when such 15 short circuit is broken, allowing relay w to attract its armature, but under the present conditions, when the line B is a called line, the relay w acts only as an element in the current supply bridge necessary to transmission of current to subscriber A.

The subscribers A and B may now converse over a metallic circuit extending from the substation apparatus at station A by way of conductors 1, a', 22, 26, 30, to the 25 substation apparatus of line B, and thence over conductors 30^a, 26^a, 22^a, a¹¹, line conductor 1, back to the substation A.

When the calling subscriber hangs up, the 30 relays c m p s become deenergized, and the entire connecting apparatus is restored to its normal condition.

Calling a busy line.

Should the line of subscriber B have been 35 already engaged when selected and tested by subscriber A, the line of the latter would have been locked out and connected with the busy signal. Furthermore, the entire train of connections set up by his selective act 40 would have been promptly dismembered and each part returned to its resting position ready for common use, with the exception of the distributor individual to the line A which would remain tied up under the control 45 of the calling station. To this end I provide electromagnetic mechanism associated with the tens and units selectors, which when its selector in response to a call makes connection with a busy line, will automatically render inert the relays c m p s controlling 50 the selectors and distributors, and cause the application of a busy test current to the calling line. The relays referred to are maintained inert until the selector arms controlled 55 thereby resume their normal positions, and until such positions have been resumed the hundreds selector, the tens-and-units finder and tens-and-units selector cannot be secured by another subscriber in the 60 act of selecting. This is obviously necessary, because every piece of selective apparatus must begin its initial operation from zero. The distributor a being a mechanism individual to each line, may remain with its re-

lay c in its operative position until the subscriber calling either hangs up or begins a new selection. A busy signal continues to be heard until one of these acts is performed.

The means which I preferably provide for accomplishing the above referred to results, 65 comprises a relay I associated with each tens and units selector. Said relay is provided with a pair of windings I² I³ respectively, the winding I² being included in a conductor 39 extending to an inner contact anvil z' of 70 a switching device z adapted to be operated by the retaining magnet of the tens and units selector each time it is energized. This switching device comprises a pair of springs z² z³, connected by a bar of insulation which 75 is adapted to be engaged by the armature of the retaining magnet u to operate said springs, the spring z² and its normal resting contact being included in the trunk conductor 26, and the spring z³ and its normal 80 resting contact being included in trunk conductor 26^a. Each time the retaining and selecting magnets are operated to step the tens and units selector arm r forward, the switching device is actuated to connect the 85 spring z² with contact z', so connecting the magnet I with the arm r of the tens and units selector. The armature I⁴ of relay I controls a short circuit 40 about the relay s, which controls at one point the circuits of 90 the magnets of the selector B'. The armature I⁵ of relay I is connected with the positive pole of battery D⁴ and controls at its 95 back contact a supply of current to the magnets of the selector B', being adapted when 100 attracted to engage its front contact, which is connected by conductor 41 with the negative pole of said battery, to provide a locking circuit including winding I⁸ of said magnet. The conductor 41 includes a pair 105 of contact springs r⁵ which are closed by the selector arm r while away from its normal position.

Since the batteries in the several bridges of the line are in practice one and the same 110 battery, it will be apparent that when the short circuit 40 is closed by relay I the magnets p m c will also be short circuited and will allow their selector arms to simultaneously commence their return to zero.

At the moment of the descent of the contact arms of the tens and units selector upon the terminals of the busy line of subscriber B, a current flows through the lock-out relay I over one of the following two paths, 115 dependent upon whether subscriber B has made or received a call. If subscriber B has already made a call, the contact spring B², which, with its resting contact, is normally included in a circuit of trunk conductor 30 120 leading from one of the terminals of the tens and units selector, will have been forced into engagement with its contact B³, which is

connected by conductor 42 with the positive pole of battery D^6 in the bridge 3^a , this spring remaining in such position until the distributor of the line B returns to its normal position. With such condition, current would flow from the positive pole of grounded battery D^6 through conductors 3^a , 42, 30, 26, through springs z^2 z' of the switching device z , which is operated by the retaining magnet when energized, thence by conductor 10 39 through the winding I^2 of the test relay I.

In case subscriber B has already received a call, the spring B^2 will not have been operated. The terminal of conductor 30 upon the tens and units selector in use by subscriber A would be connected with battery through the relays $c m p s$ of the subscriber who has already called subscriber B, and current from the positive battery pole will flow over the path outlined through relay I.

Restoration of tens-and-units selector.

In either case the relay I will be operated, and its armature contacts will bring about three results, as follows: First, armature I^5 will be disengaged from conductor 28 and deprive the tens and units selector magnets of current, thereby permitting the return to normal condition of the selector arm and the mechanism controlled thereby. Second, armature I^6 when it engages its front contact completes a local locking circuit through the winding I^3 of magnet I by way of conductors 27, 28, 41, 27. This local circuit through winding I^3 insures the locking up of relay I until the selector arm has returned to zero, for then and only then will the contacts I^5 and the locking coil I^3 be deenergized; the deenergization of relay I being then brought about by the separation of springs r^5 closed by the selector arm r when away from normal position. Third, the other armature I^4 closes a short circuit 40 around relay s for the purpose already stated of also short circuiting the relays $c m p$ in multiple with relay s .

While the tens-and-units selector is restoring its parts to normal condition, the busy test or lockout must not be removed from the terminal of conductor 26 upon the distributor E; and this is accomplished by contacts r^2 , which like contacts r^5 are closed so long as selector arm r is away from its normal resting position. These contacts continue the function previously performed by the short circuit 26^b closed by the armature s^2 of relay s^1 , this relay being now inert, since the circuit of said relay was broken as soon as the finder arm e^2 commenced its return movement, all the arms, as before stated, commencing their return movement simultaneously.

When the arm of the tens-and-units selector r has returned to its normal resting position, contacts r^6 are opened and break

the circuit through the locking winding of test relay I; relay I thereupon releases its armatures, the short circuit is removed from relay 8, and the selective apparatus is restored by armature I^5 to position for operation by other calling lines. The contacts r^2 are also opened and thus deprive the test terminal of conductor 26, upon the finder of current, and permit the use by any other subscriber of the trunk lines 26, 26^a leading to the tens and units selector B'. 70 75

Restoration of hundreds selector and tens-and-units finder.

When relays m and p are short circuited 80 by the short circuiting of relay s , as already explained, the armature m^8 in retracting closes a circuit for the magnet o which completes a short circuit 43 about the relays m and p , this short circuit taking the place 85 of the one established by the relay of the tens and units selector, which was destroyed when the finder arm e^2 left the terminal of conductor 26. The back contact of the armature m^8 of relay m is connected by 90 conductor 44 with conductor 14, which extends to the armature m^2 of relay m' , the front contact of said armature being connected by conductor 13 with the negative pole of battery D^2 , relay m' remaining at 95 attracted long enough after the short circuit 43 is closed to permit the locking of relay o . The relay o is included in the conductor 44, and when relay m is inert and relay m' energized, it will be included in a circuit 100 12', 16, 44, 14, 13, 12'. The armature o' of relay o is connected with conductor 44 between the relay o and armature m^2 , and is provided with the front contact connected by conductor 45 with the negative pole of 105 battery D^2 , said conductor including a pair of contacts h^9 closed by the arm h' of the trunk selector when away from normal position. Thus when said armature is attracted, the locking circuit 12', 16, 44, 45, 110 12', is provided for the magnet o , including battery D^2 . The armature o^2 is included in conductor 17 which supplies current to the operating magnets of the hundreds selector and tens and units finder and when said 115 armature is attracted it opens conductor 17 and permits the restoration of the arms $h' e^2$ of the hundreds selector and tens-and-units finder. While the selector arms of the hundreds selector and tens-and-units 120 finder are returning to normal position, current is kept on the contact a^2 forming a terminal of trunk conductor a' by the contacts $h^2 h^3$ which are maintained closed by the hundreds selector until it returns to normal position, relay m' being deenergized to open short circuit 15 immediately after the finder arm a^3 commences its return to zero. When the selector arm h' reaches its normal 125 position, the hundreds selector and tens-and- 130

units finder are free for the service of other calling subscribers.

Restoration of individual distributor.

5 The armature c^4 of relay c is connected by a conductor 46 with front contact of armature c^5 of relay c' , said armature c^5 being connected by the conductor 47 with the positive pole of battery D, the back contact of armature c^4 of relay c being connected by conductor 48 with bridge 3 between the relay c and the limb 1 of the line. Thus when relay c is short circuited by conductor 43, and relay c' energized, a short circuit will be established about the relay c independent of the previous established short circuit by means of conductors 48, 46, 47. The retraction of armature c^2 of relay c deprives the retaining magnet of current, and selector arms a^3 a^4 return to resting position, thus releasing trunk a' a^{11} . Relay c' continues in its operated position as long as subscriber A remains on the line, or until he begins a new selective operation by the manipulation of his interrupter. Now when relay c' is operated, and relay c is inert, the armature contacts of the two relays combine to connect a busy signal apparatus with the line of subscriber A. The busy signal apparatus Z is connected by a conductor 49 with a spring c^6 which is adapted to be moved by the armature c^4 of relay c , when said armature is attracted, out of engagement with its contact c^7 , said contact being connected by conductor 50 with the contact c^8 normally separated from its anvil c^9 , which is adapted to be operated by the armature c^5 of relay c' when attracted, to unite said contacts c^8 c^9 , contact c^9 being connected with limb 2 of the line. Thus when the relay c is inert and relay c' is energized, a circuit for the busy signal current will be completed by way of conductors 49, 50, line conductor 2, through the substation apparatus to line conductor 45 1, and thence through the bridge 3 to ground through the battery D, thus creating a busy signal in the receiver of subscriber A.

When the subscriber A hangs up his telephone, the relay c' is deenergized, and its armature c^5 disconnects the signal current from the line and breaks the short circuit about relay c . The same result is accomplished by moving the arm of the interrupter to make a new selection, for the line in that case is opened at contacts n^4 n^5 of the interrupter. Therefore either hanging up or manipulation of the interrupter arm breaks the connection of the busy signal apparatus and prepares the way for a new selection.

Outline of the operation.

The operation of my system may be briefly described as follows: The subscriber A, to initiate a call, removes his telephone from

its hook, which completes a metallic circuit including battery D and relays c c' . Relay c in drawing up its armature completes a circuit for the retaining magnet which in turn connects a test relay e with the distributor arm a^3 . If the first trunk line with which the contact arm a^3 is connected is busy, a current from battery D^2 connected with said trunk will pass through the test relay e , and so will complete a circuit for the stepping magnet d and advance the distributor arms a^3 a^4 one step. This operation will be continued until the distributor arms make contact with the terminals of a trunk line leading to an idle hundreds selector. 70 75 80

The circuit of conductors 1, 2, is now extended by way of conductors a' , a^{11} respectively to the hundreds selector, whereupon relay m' of the hundreds selector is operated to complete the continuity of conductor a' , 85 and permit the energization of relay m . The relays p p' which are in the bridge of the trunk conductors a' a^{11} , are now operated, but perform no function, since the apparatus controlled thereby is deprived of 90 current until the hundreds selector is operated. Relay m' in drawing up its armature m^8 completes a circuit for the stepping and retaining magnets, which advance the hundreds selector arm one step, or in other 95 words give it an idle onward movement.

Assuming that the called subscriber is No. 4899, the subscriber A will operate his interrupter C to step the hundreds selector to the terminals representing the hundreds 100 digit of the called line, that is, terminals 48. In operating the interrupter, the limb 1 of the line is grounded to hold up relays c m and p , and the limb 2 temporarily opened to deenergize relay m' . Relay m' thereupon retracts its armature which permits the selector arms h' to return to normal position ready for operation by the interrupter. The next step in the operation of the interrupter consists in alternately closing and opening a ground connection to the limb 2 of the line by means of the ratchet wheel d^5 and contact springs d^6 , which serve to alternately open and close contacts m^5 m^6 of relay m' and complete circuits for the 115 stepping and retaining magnets i n of the hundreds selector. When the contact arm h' of the hundreds selector reaches the 48th pair of terminals, the interrupter is restored to normal position and the metallic 120 circuit again renewed. This allows the relay i to remain energized an instant, whereupon the connecting magnet k of the hundreds selector is allowed to operate, disconnecting the stepping and retaining magnets from the hundreds selector arm, drawing the selector arm h' down upon the contact terminals 48. The selector arm h' when away from normal position, closes contacts h^4 , and when the connecting magnet is op- 125 130

erated contacts h^5 are closed, so furnishing current from battery D^2 to the local circuits of the tens and units finder E . Relay p^1 is now operated to complete a circuit for the test relay q^2 , and in case the first trunk line is engaged, it will close a circuit for the stepping and retaining magnets $q^1 q^2$ to advance the finder arms e^2 successively to the terminals of an idle trunk line. The finder E operates in precisely the same manner as the individual distributor a of the calling line.

Let us assume that the first idle pair of trunk conductors is 26, 26^a, leading to tens and units selector B' . When the arms e^2 are connected with the terminals of conductors 26, 26^a, a circuit is completed for relay s' in the bridge 27 by way of trunk conductors 26^a, 22^a, a^{11} , line conductor 2 to the substation apparatus and back by way of limb 1 of the line through the bridge 3 to the positive pole of battery D . The armature s^2 of relay s' , in drawing up completes the continuity of conductor 26, and applies a test potential from battery D^4 to the terminals of this trunk conductor upon the different finders. The completion of the continuity of this conductor allows relay s to operate. The subscriber may now operate the tens and units selector in exactly the same manner as he operated the hundreds selector to bring the contact arms r into connection with the 60th pair of terminals which lead to the substation of the desired line, the connecting magnet v being operated when said connection is completed to draw the arms down against the terminals of the line and to disconnect the stepping and retaining magnets $t u$ from the selector.

When the tens and units selector makes connection with conductors 30, 30^a, leading to the called station, a circuit is completed through the relay F , including battery D^4 , which serves to disconnect the distributor of a called line and its associated apparatus therefrom. The armature F^2 of said magnet also connects an impedance coil x' in multiple with the relay w of such line, and the armature F' of said relay F includes an impedance coil x in multiple with the relay w' of such line, for the purpose of balancing the line for transmission purposes as hereinbefore explained.

The subscriber A now signals the called party by depressing his ringing key y , which grounds the limb 1 of the line, opening the limb 2 of the line, whereupon relay s , being energized, attracts its armature s^3 , and relay s' being inert, the ringing generator G is connected with the conductor 26^a leading to the substation B of the called line, current from said generator flowing over conductors 35, 34, 26^a, 30^a, through the bell

at the called station and back over conductors 30, 3^a, 33, 34^a, 3^b, to earth.

In case the called line is busy, current will be found on the terminals of conductor 30, at the tens and units selector, and the switching device z being operated, such current would be applied to the relay I , which would short circuit the relays $s p m$ and c , depriving the connecting and retaining magnets of the selectors, distributor and finder of current, and allowing the distributor, finder and selector arms to return to zero, and in addition applying busy test to the calling line under the control of relays $c c'$.

I claim:

1. In an automatic telephone exchange, the combination with a number of telephone lines extending from substations to a central office, of hundreds selectors at the central office, each having contacts representing the hundreds digits terminals of said lines, a distributor for each line at the central office adapted to select an idle hundreds selector, means at the calling station for operating said selector to connect said line with the hundreds digit terminal of the called line, a number of groups of tens-and-units selectors, the selectors of each group having contacts representing the tens-and-units digits associated with a given hundreds digit, a finder associated with said hundreds selector adapted to connect said hundreds digit terminal with an idle tens-and-units selector having its associated tens-and-units digit terminals thereon, means for operating said distributor and finder, and means at the calling station for operating said idle tens-and-units selector to complete the connection of the calling line with the desired line.

2. In an automatic telephone exchange, the combination with a number of telephone lines extending from substations to a central office, of a source of current in each line at the central office, a switch at the substation of each line controlling the flow of current therein, a number of hundreds selectors at the central office, each having contacts representing the hundreds digits of the lines in the exchange, a distributor for each line at the central office responsive to the flow of current in the line, adapted to connect said line with an idle hundreds-selector, means at a calling station for operating said idle selector to connect said line with the contacts representing the hundreds digit of the called line, a number of groups of tens-and-units selectors at the central office, each selector of a group having contacts representing the tens-and-units digits associated with a given hundreds digit terminal, a finder associated with said hundreds digit terminal responsive to current in the calling line, adapted to select an idle tens-and-units selector, carrying terminals of the line having ten-and-

units digits associated with said hundreds digit, and means at the calling station for operating said tens-and-units selector to complete connection with the desired line.

- 5 3. In an automatic telephone exchange system, the combination with a number of telephone lines extending from substations to a number of sets of terminals at a central office, of hundreds and tens-and-units 65
10 selectors at the central office, means controlled from the station of the calling line for operating said selectors to connect said line with a terminal of the called line, mechanism operated in making such connection for cutting off the idle line terminals of the calling line and applying a test potential thereto, and means actuated upon the operation of the tens-and-units selector for applying a test potential to the remaining line terminals 70
15 of the called line.
- 20 4. In an automatic telephone exchange, the combination with telephone lines extending from substations to a central office, of hundreds and tens-and-units selectors at 75
25 the central office for connecting a calling and a called line, electromagnetic mechanism for operating each connecting device, a magnet I, a circuit therefor completed when connection is completed by said tens-and-units
30 selector with a busy line, said magnet being adapted to render said electromagnetic mechanism inert, means for restoring said 80
35 selectors to normal position, and means actuated when said electromagnetic mechanism is rendered inert for applying a busy signal to the calling line.

- 5 5. In an automatic telephone exchange, the combination with telephone lines extending from substations to a central office, of 85
40 hundreds and tens-and-units selectors at the central office for connecting a calling and a called line, a relay controlling each selector, circuits for said relay controlled from a calling station, a relay I, a circuit therefor completed when connection is made by said 90
45 selectors with a busy line, and shunts about said selector relays closed by said magnet when energized, and means for returning said selectors to normal position when their
50 relays are deenergized.

6. In an automatic telephone exchange, the combination with telephone lines extending from substations to a central office, of hundreds 95
55 selectors at the central office, a distributer individual to each line adapted to connect the same with an idle hundreds selector, a number of tens-and-units selectors, finders associated with the hundreds selector for connecting the same with an idle tens-and-units selector in response to calls, a relay for each distributer, selector and finder controlling the operation thereof, circuits for said relays controlled from a calling station, a relay I, a circuit therefor completed 100
60

when connection is made by the tens-and-units selector with a busy line, short circuits about the relays controlling the connecting devices closed by said relay I when energized to release said connecting devices, means for returning said devices to normal position, and means actuated when said relays are short circuited for applying a busy signal to the calling line.

7. In an automatic telephone exchange, the combination with telephone lines extending from substations to a central office, of a number of hundreds selectors at the central office, a distributer individual to each line, and adapted to connect the same with an idle hundreds selector, a relay c controlling 80
85 said distributer in a circuit controlled from the station of such line, tens-and-units selectors, means actuated by a selected hundreds selector for connecting an idle tens-and-units selector therewith, relays controlling said selectors, circuits for said relays controlled from the calling station, means actuated when connection is made by the tens-and-units selector with a busy line for rendering said relays inert, means for returning said selectors and distributer to normal position when released, a relay c' in said circuit, and a source of busy current adapted to be applied to the calling line by the coöperation of said relays c c'. 90
95

8. The combination with a number of telephone lines extending from substations to a central office, of a number of hundreds selectors at the central office, an individual distributer for each line at the central office, means controlled from a calling station for operating its distributer to select an idle hundreds selector, each hundreds selector having contacts representing the hundreds digits of the said lines, means 100
105 controlled from the calling station for operating said idle selector to make connection with the hundreds contact of a called line, a number of groups of tens-and-units selectors, the selectors of each group having contacts representing the tens-and-units digits associated with a particular hundreds digit, a finder associated with each hundreds digit contact responsive when such contact is connected with a calling line, for connecting 110
115 the said contact with an idle tens-and-units selector, means controlled from the calling station for operating said idle tens-and-units selector to complete connection with a desired line, and means for establishing a test 120
125 potential at the contacts of such called line upon the remaining tens-and-units selectors connected therewith.

9. The combination with a number of telephone lines extending from substations to a central office, of a number of hundreds selectors at the central office, an individual distributer for such line adapted

- to connect said line with an idle hundreds selector, tens-and-units selectors, finders associated with the hundreds selectors for connecting the same with idle tens-and-units selectors, means controlled from a calling station for operating the selected hundreds and tens-and-units selectors to make connection with a called line, and mechanism actuated when connection is made with a busy line
- 10 for applying a busy signal to the calling line and restoring the connecting devices to normal position independent of the calling line.
10. In an automatic telephone exchange, the combination with a number of metallic circuit telephone lines extending from substations to a central office, of a number of hundreds selectors at the central office, a distributor individual to each line adapted to connect such line with an idle hundreds selector, mechanism for operating said distributor controlled from the station of its line, a number of tens-and-units selectors, a finder associated with the hundreds selector actuated when a calling line is connected thereto for connecting said hundreds selector with an idle tens-and-units selector, mechanism controlled from the calling station for operating said selected selectors, and a relay in a bridge of the called line
- 20 adapted to be connected with a source of current by said tens-and-units selector when the same is connected with the called line for temporarily depriving the mechanism of the individual distributor of the called line of current.
- 30 11. In an automatic telephone exchange, the combination with telephone lines extending from substations to a central office, of hundreds and tens-and-units selectors at the central office for connecting a calling and a called line, electromagnetic mechanism for operating each selector controlled from a calling station, means for automatically returning said selectors to normal position when connection is made with a busy line, and means for preventing the access of other calling lines to said selectors until the same have reached their normal positions.
- 40 12. The combination with telephone lines extending from substations to a central office, of a number of line selectors at the central office, each line selector comprising a contact arm adapted to sweep over line terminals, a distributor individual to each line at the central office, a number of trunk lines extending from the contact arm of each selector to a number of individual distributors, means controlled from a calling station for operating its distributor to connect said line with a trunk line leading to an idle selector, means controlled from the calling station for operating the contact arm of the selected selector to make connection with a desired line, a source of current associated
- 50 60 65 with each selector, means for applying cur-

rent from said source to the other trunk lines connected with said selector the instant said distributor made connection with said trunk line leading to said selector, and normally open contacts closed by said selector 70 arm while away from its normal position for connecting said source with the remaining trunk lines leading to the other distributors associated with said selector.

13. The combination with a calling and a called telephone line, of connecting devices for uniting said lines, a source of current in a branch of the line uniting said stations, a number of relays in multiple between said branch and the connected lines, a condenser 80 interposed between the connection of one of said relays with the line and the point of connection of the other relays, and means actuated when connection is completed between the lines for interposing resistance in 85 multiple with said relay to provide an adequate current supply for transmission.

14. In an automatic telephone exchange, the combination with a calling and a called telephone line, of magnetically operated connecting devices and their trunk lines for uniting said lines in metallic circuit, relays for operating said connecting devices, a source of current in a bridge of the connected lines, condensers in the limbs of the line 90 between the stations, multiple branches of said bridge to both sides of the line including said relays, a multiple branch including a relay being connected with each limb of the line between the condensers and the 95 called station to supply talking current to the called station, a pair of inductive resistances, and a relay in a circuit closed upon the completion of connection between the lines, for connecting said inductive resistances in multiple with the relays in the branches supplying current to the called line; whereby an adequate current supply 100 for voice transmission is provided.

15. The combination with a number of 110 telephone lines, of distributors, finders and selectors for uniting a calling and a called line, relays $c' m' p' s'$ controlling the operation of said distributors, finders and selectors, a circuit for said relays controlled from 115 a calling station, relays $c m p s$ in a circuit controlled from the calling station, means actuated when said distributors, finders and selectors complete their connections for transferring the control of said devices from 120 relays $c' m' p' s'$ to relays $c m p s$, a source of ringing current, means actuated when relay s is energized and relay s' inert for applying said ringing current to the calling line, and a ringing key at the calling station 125 for completing the circuit of relays $c m p s$ and opening the circuits of relays $c' m' p' s'$; whereby ringing current is applied to the called line and the distributors, finders and selectors held in their operated position. 130

16. In an automatic telephone exchange, the combination with telephone lines, of selectors for uniting a calling and called line, means controlled from the calling station for operating said selectors to make connection with a desired line, relays for holding said selectors in their operated position, a shunt of each relay closed when connection is made with a busy line, means for restoring said selectors to normal position when released by their relays, and means for applying busy test to the terminals of each selector until it reaches normal position.
17. In an automatic telephone exchange, the combination with telephone lines, of hundreds and tens-and-units selectors for uniting a calling and a called line under the control of a calling station, relays and a circuit therefor for holding up said selectors, a shunt 40 about said relays closed when connection is made with a busy line to permit said selectors to return to normal position, independent short circuits closed about said relays upon the closure of short circuit 40 until the selectors reach zero, and contacts closed until the selectors reach zero for applying a test current to the terminals of said selectors.
18. In an automatic telephone exchange, the combination with a selector, of two-wire telephone lines terminating at pairs of terminals upon said selector, one side of each line having a normal break therein, a switch contact for closing said break, a relay operated when a connection is made to any line for operating said contact to complete the transmission circuit, and a source of current adapted to be connected through said contact to the line terminal to establish a test potential thereon, said selector having electromagnetic mechanism for advancing its brushes when said brushes rest upon busy terminals having such test potential.
19. The combination with a number of telephone lines, of automatic selectors for uniting any two lines, relays controlling the operation of said selectors in circuits controlled from the calling station, a relay adapted to apply ringing current to the called line, a circuit therefor controlled from the calling station, which circuit controls the circuits of the selector relays, additional relays in the circuit of said ringing relay, and means for transferring the control of said selectors to said additional relays.
20. In a telephone exchange system, the combination with telephone lines terminating in a central station, of automatic selectors adapted to extend the circuit of a calling line to a group of lines according to the first digit of the designation of the desired line, switching mechanism for connecting a calling line with an idle one of said selec-
- tors, additional automatic selectors adapted to further extend the circuit of a calling line according to the succeeding digits of the designation of the desired line, a finder associated with each of said first mentioned 70 selectors for connecting it to a desired idle one of said additional selectors, and means for controlling said selectors.
21. In a telephone exchange system, the combination with telephone lines, of automatic selectors, switching apparatus for connecting a line taken for use with an idle one of said selectors, groups of additional selectors, such groups being adapted to be selected by said first mentioned selectors, 80 finder mechanism operating after the selection of a group of said additional selectors by one of said first mentioned selectors to connect it to an idle one of such group, and means for controlling said selectors.
22. In a telephone exchange system, the combination with telephone lines each terminating in a plurality of sets of terminals at a central station, of connecting circuits at such central station adapted to interconnect 90 such lines, means operated in the connection of one of said connecting circuits with terminals of a calling line for causing the disconnection of the remaining line terminals of such line, and means operated when 95 one of said connecting circuits completes the connection by uniting with the terminals of the called line for applying a test potential to the remaining line terminals of such line.
23. In a telephone exchange system, the combination with telephone lines each terminating in a plurality of sets of terminals at a central station, of connecting circuits at such central station, automatic switching apparatus co-operating with such connecting 100 circuits to interconnect said lines, means operated in the connection of one of said connecting circuits with terminals of a calling line for causing the disconnection of the remaining terminals of such line, and 105 means operated by the connection of such switching apparatus with terminals of a called line for applying a test potential to the remaining terminals thereof.
24. In a telephone exchange system, the combination with telephone lines terminating in a central station, of automatic switching apparatus at such central station for interconnecting said lines, power means in said switching apparatus to cause it to complete connection with a desired line, a test relay operated when said switching apparatus makes contact with the terminals of a busy line, restoring means for said switching apparatus controlled by the operation 115 of said test relay, and means also controlled by said test relay for applying a busy signal to the calling line.
25. In a telephone exchange system, the combination with telephone lines terminat-

ing in a central station, of a train of automatic selectors adapted to extend the circuit of a calling line, electromagnetic means controlling the operation and restoration of 5 said selectors, and means for preventing access to said selectors during restoration.

26. In a telephone exchange system, the combination with telephone lines terminating in a central station, of a train of automatic 10 selectors adapted to extend the circuit of a calling line, electromagnetic mechanism for operating said selectors, means for returning said selectors to normal position, and means for preventing access to said 15 selectors during such restoration.

27. In a telephone exchange system, the combination with telephone lines terminating in a central station, of a train of automatic 20 selectors adapted to extend the circuit of a calling line, electromagnetic mechanism for operating said selectors, means for returning said selectors to normal position when brought into contact with the terminals of a busy line, and means for preventing 25 access to said selectors during such restoration.

28. In a telephone exchange system, the combination with telephone lines terminating in a central station, of a group of automatic 30 selectors less in number than the number of said lines, switching apparatus for connecting a line taken for use with an idle one of said selectors, electro-magnetic mechanism for bringing such selector into position 35 to extend the desired connection, means for restoring such selector to normal when brought into contact with the terminals of

a busy line, and means for preventing the seizure of such selector by said switching apparatus during such restoration.

29. The combination with a telephone line extending from a substation to a central office, of a connecting circuit at the central office, a distributor for uniting said connecting circuit with the line, mechanical line 45 switching mechanism adapted to unite said connecting circuit with a desired telephone line, means for operating said switching mechanism, and means for preventing the use of said switching mechanism when released until the same has returned to normal position.

30. In a telephone exchange system, the combination with a telephone line extending from a substation to a central office, of a connecting circuit at the central office, a connecting switch for uniting said connecting circuit with the telephone line, an automatic connector adapted to unite said connecting circuit with other telephone lines, 60 sending apparatus adapted to be set by the operator to actuate said connector, and means for preventing the use of said connector after the connection is taken down until said connector is restored to normal 65 condition.

In witness whereof, I, hereunto subscribe my name this fifth day of March A. D., 1906.

ALBERT M. BULLARD.

Witnesses:

JENNIE C. LAMB,
GEORGE A. HAMILTON.
